(57) **CLAIM**

The ornamental design for a bicycle rim, as shown and described.

DESCRIPTION

FIG. 1 is a perspective view of a bicycle rim showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a cross-sectional view taken along line 8-8 of FIG. 2;

FIG. 9 is an enlarged view of the part A of FIG. 8;

FIG. 10 is a cross-sectional view taken along line 10-10 of FIG. 2; and,

FIG. 11 is an enlarged, broken away perspective view of a part of FIG. 1.

The broken lines in the drawings illustrate portions of the bicycle rim that form no part of the claimed design. The dot-dash lines indicate boundaries of the claimed design, and form no part thereof.
